UNITED STATES PATENT OFFICE.

ABRAHAM B. LANDIS, OF ENFIELD, PENNSYLVANIA.

BOLT-THREADING MACHINE.

1,112,539.

Specification of Letters Patent.

Patented Oct. 6, 1914.

Application filed March 31, 1911. Serial No. 618,212.

To all whom it may concern:

Be it known that I, ABRAHAM B. LANDIS, a citizen of the United States, residing at Enfield, in the county of Montgomery and State of Pennsylvania, have invented certain new and useful Improvements in Bolt- Threading Machines, of which the following is a specification.

The object of my said invention is to provide an automatic bolt cutting machine wherein the operation will be continuous and rapid and the construction of which will be comparatively simple, inexpensive and durable, all as will be hereinafter more fully described and claimed.

Referring to the accompanying drawings, which are made a part hereof, and on which similar reference characters indicate similar parts. Figure 1 is a side elevation of a bolt cutting machine of my improved construction, a portion of the casing being broken out to illustrate internal features of construction more clearly, Fig. 2 a view partly in transverse section and partly in end elevation, as seen when looking in the direction indicated by the arrows from the dotted line 2--2 in Fig. 1, Fig. 3 a detail view partly in side elevation and partly in section, as seen when looking in the direction indicated by the arrows from the dotted lines 3--3 in Fig. 2, Fig. 4 a detail section on the dotted line 4--4 in Fig. 3, and Figs. 5, 6, 7, 8 and 9 detail views illustrating separate features of construction more clearly.

In said drawings the portions marked A represent the bed of the machine, B the cutter-head and C the work-carriage.

The machine bed A and cutter-head B are, in the main, of any appropriate or approved form and require no special description, my present invention relating more particularly to the mechanism for feeding and holding the work to the die. Said parts will therefore only be described incidentally in describing the other features of the invention.

The work-carriage C is a suitable casting adapted to carry the various parts of the mechanism and mounted to stand in a vertical position and slide on tracks comprising rods 5 and 6 which are supported one above the other by suitable standards on the frame A. An adjustable yoke C' is also mounted on said bars 5 and 6 adjacent to the rear end of said carriage and held in adjusted position by means of a dog 7 engaging with the teeth of a rack-bar 8 formed on the top

of rod 6 at this point for a purpose to be presently described. A rod 10 is pivotally connected at 11 to the lower end of a forked lever 12 which is fulcrumed at 13 to a bracket or arm a⁵ connected with the frame A. Said forked lever embraces the cutter-head and at 14 carries rollers which engage a circumferential groove in said head for operating the opening and closing mechanism in the usual, or any approved, manner. Said rod 10 extends through a depending lug c on carriage C, and a nut 15 is adjustably mounted on the adjacent screw-threaded portion to regulate the time of contact and consequent operation.

Carriage C is formed with a central boss c' extending out transversely therefrom in which is formed a bearing and in said bearing is journaled a hollow shaft 16 on the rear end of which is mounted a work carrying and supporting turret 17. Said shaft 16 is formed with a spiral toothed portion 18 with which a worm gear 19 is adapted to engage. Said worm gear 19 is formed on a sleeve which is mounted on the carriage driving shaft 20. The outer end of said carriage driving shaft is screw-threaded, as best shown in Fig. 3, but the interior of said sleeve is smooth, permitting it to slide freely thereon. One end of said sleeve 19 is formed flanged to abut against the adjacent side of boss c' and a cup-shaped rim 21 is formed around said flange to serve as one part of a clutch. The other clutch part 22 is connected to shaft 20 by means of a spline 23 which slides in a groove in shaft 20 and is secured in a groove in the hub of part 22 by a set-screw s. A flanged nut 24 is mounted on the outer end of the clutch part 21 on sleeve 19 the flange surrounding the hub of part 22 so that but a short independent longitudinal movement is permitted between said clutch parts. A collar 25 surrounds shaft 20 within a perforation in yoke C' and a coiled spring 26 is mounted between a flange on ring 27 screw-threaded into the outer end of said perforation and a flange formed on the inner end of said collar, said spring being thus mounted to normally hold said collar forward against the hub of clutch part 22. A spline s' is mounted in a groove in the top side of perforation containing collar 25 and engages a notch in the flange of said collar to hold it from turning.

A half nut 30 is mounted on a pivot 31 between lugs 32 on the side of the carriage

and is normally held by means of spring 33 into engagement with the screw-threaded portion of shaft 20 so that the turning of shaft 20 will operate to slide said carriage 5 on the tracks 5 and 6. A stationary concave-faced lug 34 mates with the hinged nut 30 to surround said shaft 20, but is not formed screw-threaded. A trip bar 35 pivoted at one end to a link 36 and at its other end to bell crank lever 37 is mounted on bed 16. Adjacent to the lower end of an arm 38 extending from the lower side of nut 30 below its pivot 31. Link 36 is pivoted at its other end to the bed and lever 37 is pivoted 15 at point 39 in line with said pivot of link 36. The opposite angle of lever 37 is bifurcated and engages with a circumferential groove in a collar 40 on rod 10 for a purpose to be presently described.

20 The rear end of rod 10 is formed with threads or rack teeth 41 with which the teeth of a pivoted dog 42 are adapted to engage. Said dog 42 is pivoted on the carriage C (see Fig. 7) and is normally held against 25 a stop pin 43 by a spring 44 out of engagement with said teeth. A spring shoe 45 is mounted on the lower edge of yoke C' in position to throw dog 42 downward into engagement with the teeth in said rod 10 as 30 carriage C moves into position for the end of said dog to pass under said shoe. I have shown the teeth in section 41 of shaft 10 in the form of spiral threads, which I regard as of advantage in enabling a fine adjustment to be secured, but a rack-bar formed 35 on one side of rod 10 only will, of course, be operative.

Turret 17 mounted on the rear end of hollow shaft 16 is formed, as best shown in Figs. 8 and 9, with a rim 45 having a series 40 of radial perforations through which the bolts constituting the work are adapted to extend and having an internal groove or recess of a size adapted to receive the heads 45 of said bolts to hold them from turning. A magazine 46 is mounted by means of a supporting brace 46 to guide the work from a source of supply (such as any appropriately arranged hopper, not shown,) to within the 50 rim 45 on the turret wheel 17, said work being dropped from the end of said magazine into a chute 48 (Fig. 8) which guides them to the bottom of the wheel where they will slide, one by one, through the radial perforations as said turret is rotated step by step 55 to bring said perforations in line with said chute.

Opposite each perforation in rim 45 is formed a notch *n* in the side of turret 17 60 with which a latch bolt 67 is adapted to engage. Said latch bolt 67 is mounted in a transverse perforation in carriage C and is normally held into engagement with one of said notches by a spring 68. Said bolt is 65 formed with a notch having a tapered face *t*

with which a tapered inner end of a sliding cam 65 engages. The outer end of said cam 65 projects beyond the edge of carriage C and is adapted to strike a shoulder on a pivoted trip 66. Said trip 66 is pivoted by a ball pivot in a seat in the end of an adjusting screw 70 mounted in yoke C' and is normally held against a stop pin 71, in position to strike end of cam 65, by means of a spring 72. The forward end of said trip extends 75 beyond the shoulder against which end of cam 65 strikes to a point near the adjacent corner of carriage C formed tapered and adapted to contact with a tapered face *c* on said corner of carriage C immediately after 80 said cam 65 has been operated to disengage locking bolt 67 from turret 17. Pivoted strike 66 is thus thrown away from cam 65 and spring 68 permitted to throw bolt 67 into the next notch *n* as soon as turret 17 advances to a point to bring said notch to register therewith. By adjusting screw 70 the operation of the parts may be timed and regulated to a very fine degree.

85 Mounted within hollow shaft 16 is a solid shaft 50 having a flanged cap 51 on its outer end, which surrounds the end of boss *c*' on the carriage C, to which it is secured by a set-screw 52. Said cap is secured to the end of shaft 50 by a pin 53, thus holding said 90 shaft stationary. A hub *h* is rigidly secured on the opposite end of said shaft and supports an arm 54 having a segmental shoe 55 on its outer end on the face of which is mounted a spring guide 56 in close proximity to the inner face of the rim 45. Said 95 spring guide may be adjusted in its relation to said rim 45 by means of set-screw 57. A chute 58 is also mounted on the outer end 100 of said hub, the upper end of which is in position to receive the work from the top of rim 45 of turret 17 and the lower end of which is arranged to discharge the finished work into a receptacle 59 located in the bed 105 of the machine.

110 The operation of the machine is as follows: The parts being adjusted as shown in Fig. 1, the bolt blanks come to the revolving turret 17 from the magazine 46 and slide down chute 48, one by one, the points of the 115 blanks passing through the perforations in said rim as indicated. The main shaft 1 is driven from pulleys 2, the motion of which is transmitted through a gear 3 on said shaft 1 to an intermediate gear 4 and from thence to a gear 60 on the carriage driving shaft 20. As said carriage driving shaft is 120 revolved, the nut 30 being in engagement with the screw-threaded part of said shaft, carriage C is slid forward on its tracks to carry the bolt to the die B the driving gear being adjusted to feed said carriage at a speed corresponding to the pitch of the thread being cut. Nut 15 on rod 10 is also 125 adjusted to regulate the length of thread to 130

- be cut on the work. When arm *c* on carriage *C* strikes said nut 15, rod 10 is forced forward which, through the lever 12 and connections with the cutter-head, operates 5 the mechanism to open the die and, at the same time, through the bell crank lever 37, operates to throw the trip bar 35 inwardly against the lower end 38 of the arm on pivoted nut 30, throwing said nut out of engagement with shaft 20. Immediately upon said nut being released from shaft 20 weight 61 operates through flexible connection 62, which runs over idler pulleys 63 and 64 to a connection with carriage *C*, to slide said carriage rearwardly on the bars 5 and 6 until the outer end of dog 42 comes under spring shoe 45 on yoke *C'* which throws said dog downwardly into engagement with the rack section 41 of rod 10 and forces 10 said rod rearwardly, operating through the connection with the cutter-head to close the die and at the same time retract trip bar 35, permitting spring 33 to again reengage nut 30 with the threaded portion of the carriage 15 operating shaft 20 and repeat the forward movement of the carriage carrying the work. As carriage *C* reaches the limit of its rearward motion the outer end of the sliding cam 65 strikes the shoulder of the pivoted 20 trip 66 forcing said cam inwardly, its tapered face operating upon the tapered face of the notch in latch bolt 67 to withdraw said latch bolt from engagement with the notch *n* in turret 17, freeing said turret 25 from its lock. The continuation of the movement of carriage *C* immediately breaks the connection between parts 65 and 66 and permits spring 68 to reengage bolt 67 to lock 30 turret 17 at the next notch *n*, as before described. As soon as turret 17 is unlocked the outer end of the hub of clutch part 22 contacts with the face of spring mounted 35 sleeve 25 in yoke *C'*, forcing the two clutch parts together and operating worm 19 to turn hollow shaft 16 and, through it, wheel 17 until the next notch *n* opposite the next radial perforation in turret 17 is reached, when spring 68 operates to throw bolt 67 to 40 engage with said notch and lock said wheel in position to receive the next blank at its lowermost hole and bring the blank carried in the perforation opposite the die in position for said die to operate upon. As the wheel 16 rotates the heads of the bolts pass 45 under the end of spring shoe 56 which serves to press the heads of said blanks firmly to their seats in the groove in the rim 45, the heads being thus held from turning during the process of cutting. Bolt 57 furnishes a rigid support for the thrust of the work at the beginning of the cutting and the shoe 56 holds the bolt in position until it reaches the position at the top of the turret where it falls from the upper end of said shoe and 50 will drop into chute 58 and be conducted to the receptacle 59 in the bed of the machine. By adjusting yoke *C'* and the parts carried thereby any length of bolt desired may be operated upon and the travel of the carriage *C'* correspondingly regulated. By adjusting the nut 15 on rod 10 the length of the cut or thread on the work may be regulated as desired. 55
- Having thus fully described my said invention, what I claim as new and desire to secure by Letters Patent, is:
1. An automatic bolt threading machine comprising a bed, a cutter-head, a reciprocating work carriage, means for feeding the work, a screw-shaft for operating said reciprocating carriage, a pivoted part carrying a nut portion adapted to be normally held into engagement with said screw-shaft, a trip bar for throwing said nut section out of engagement with said screw-shaft, a sliding rod connected with the mechanism for opening and closing the die, a connection between said sliding rod and said trip bar, whereby said trip bar is operated as the die is opened to release said nut part from said screw-shaft, and means for sliding said work carriage away from the cutter-head as soon as said die is opened and the nut part released, substantially as set forth. 60
2. An automatic bolt threading machine comprising a bed, a cutter-head embodying a die, means for operating the same, a work carriage, means for feeding the work, a gear for feeding said work carriage to the cutter-head, means for opening the die and releasing said gear when the cutting operation is completed, a transverse shaft, a turret mounted thereon, a clutch connection between the carriage feeding gear and the shaft of the turret wheel, means for engaging said clutch to move said turret wheel forward one step at the limit of the rearward motion of the carriage, means for unlocking said turret just prior to the engagement of said clutch, and means for operating the die closing mechanism at the limit of the rearward movement of said work carriage, substantially as set forth. 65
3. An automatic bolt cutting machine comprising a bed, a cutter-head, means for operating the same, a reciprocating work carriage, a carriage operating screw-shaft, a pivoted nut part carried by said work-carriage for engaging with said screw-shaft for operating it in a forward direction, means for disengaging said nut part at the completion of the work, means for sliding said work carriage rearwardly on its track while said nut part is disengaged, a connection with the die opening and closing mechanism arranged to be operated by said work-carriage, a contact between said work-carriage and said connection at the limit of the rearward motion of said carriage for operating the same and also reengaging the nut part. 70

with the screw-shaft, and means for feeding the work, substantially as set forth.

4. An automatic bolt cutting machine comprising a bed, a cutter-head, mechanism for opening and closing said cutter-head, a rod connected with said mechanism for operating the same, a reciprocating work carriage mounted on tracks on said bed, connections between said carriage and said rod for sliding the same to operate the opening and closing mechanism, a gear for operating said carriage in a forward direction, means operated by said rod for disengaging said gear at the opening of the die, means for returning said carriage to contact with an adjustable yoke mounted on its track, said yoke, means for adjusting said yoke to regulate the length of movement of said carriage, means carried by said yoke for engaging the carriage with said rod, a turret on said carriage for receiving and presenting the work to the die, a gear connection between said carriage operating gear and the shaft of said turret, and means for throwing said gear into engagement at the limit of the rearward movement of said carriage, substantially as set forth.

5. An automatic bolt threading machine comprising a bed, a cutter-head, a reciprocating work-carriage, an adjustable yoke mounted on the tracks of said carriage, a connection for opening and closing the head, and adjustable strikes between said connection and said work-carriage whereby said connection is operated, one of which is carried by said adjustable yoke, substantially as set forth.

6. An automatic bolt threading machine comprising a bed, a cutter-head, a reciprocating work-carriage, a connection between said reciprocating work-carriage and said cutter-head for opening and closing the die, a dog carried by said carriage for engaging rack-teeth formed on said connection, and an adjustable strike for throwing said dog into engagement with said rack-teeth at a predetermined point, substantially as set forth.

7. An automatic bolt threading machine comprising a bed, a cutter-head, a reciprocating work-carriage, means for reciprocating said work-carriage, a connection between said work-carriage and said cutter-head for opening and closing the die, a rotary turret on said work-carriage for receiving and holding the work to the cutter-head, means for operating said turret step-by-step to present the bolt blanks to said cutter-head successively, means for locking said turret at the completion of each step of its movement, and means for rigidly supporting said bolt blanks in said turret while being operated upon, substantially as set forth.

8. An automatic bolt threading machine comprising a bed, a cutter-head, a recipro-

cating work-carriage, a screw-shaft for operating said work-carriage, a sleeve on said screw-shaft carrying a worm-gear, a clutch mechanism for locking said sleeve to said screw-shaft at a predetermined point, a rotary turret journaled in a bearing on said reciprocating carriage, a gear on the journal of said turret engaging with the worm-gear on said sleeve, means for locking said turret at predetermined points, and means for feeding the work blanks to said turret, substantially as set forth.

9. An automatic bolt threading machine comprising a bed, a cutter-head, a reciprocating work-carriage, a screw-shaft for operating said work-carriage, a work carrying turret on said carriage, a gear for operating said turret intermittently, and clutch mechanism for engaging said gear with said screw-shaft at predetermined intervals, substantially as set forth.

10. An automatic bolt threading machine comprising a bed, a cutter-head, a reciprocating work-carriage, a connection between said cutter-head and said work-carriage for opening and closing the die, a rotary turret journaled on said work-carriage for receiving and presenting the work to said cutter-head, means for feeding the work to said rotary turret, a screw-shaft for operating said receiving work-carriage, and a gear embodying a clutch connecting the turret with said screw-shaft whereby said turret is operated intermittently, substantially as set forth.

11. An automatic bolt threading machine comprising a bed, a cutter-head, a reciprocating work-carriage, a work-carriage operating shaft, a rotary turret on said work-carriage, and clutch mechanism connecting said rotary turret with said operating shaft, whereby said turret may be operated intermittently, substantially as set forth.

12. An automatic bolt threading machine comprising a bed, a cutter-head, a reciprocating work-carriage, a screw-shaft for operating said work-carriage, a rotary work-carrying turret on said work-carriage, a gear carried by said work-carriage and connected to operate said turret, and a clutch for securing said gear to turn with said screw-shaft at intervals, substantially as set forth.

13. An automatic bolt threading machine comprising a bed, a cutter-head, a reciprocating work-carriage, a screw-shaft operating said work-carriage, a work-carrying turret journaled in said work carriage, an adjustable yoke arranged at the limit of the rearward movement of said work-carriage, a gear connection between the journal of said turret and said screw-shaft embodying a clutch, and a yielding collar mounted on said yoke in position to turn in said clutch at the limit of the rearward movement of

comprising a bed, a cutter-head, a work-carriage, whereby said turret is advanced one step, substantially as set forth.

14. An automatic bolt threading machine comprising a bed, a cutter-head, a reciprocating work-carriage, a rotary work-carrying turret on said work-carriage, a screw-shaft for operating said work-carriage, a loose gear connection between the journal of said turret and said screw-shaft, a clutch part for throwing said gear into operative connection, and means for operating said clutch at the limit of the rearward movement of the carriage, substantially as set forth.

15. An automatic bolt threading machine comprising a bed, a cutter-head, a reciprocating work-carriage, means for operating said work-carriage, a work-carrying rotary turret journaled on said work-carriage, a lock for securing said turret in each position, a sliding cam engaging with the bolt of said lock for disengaging the same, a pivoted strike mounted on a frame adjacent to said carriage and in position to operate said cam at the limit of the rearward movement of said carriage, and means for throwing said strike out of engagement with said cam after withdrawing said bolt and unlocking the turret, substantially as set forth.

16. An automatic bolt threading machine comprising a bed, a cutter-head, a reciprocating work-carriage, means for operating said carriage, a revolving work-carrying turret journaled on said work-carriage, means for operating said turret, a magazine for feeding the work to said turret, said turret being formed with radial holes and an interior groove adapted to receive and hold the bolt heads, and a spring shoe adjacent to said groove for forcing said bolt heads to their seats therein, substantially as set forth.

17. An automatic bolt threading machine

riage, means for operating said work-carriage, a rotary work-carrying turret journaled on said work-carriage, means for operating said turret, a magazine for feeding the work to said turret, said turret being formed with a recess in the interior of its rim adapted to receive and hold the bolt heads, a shoe with a segmental face supported on an arm from a hub mounted around the axis of said turret, and a spring guide mounted on said shoe for forcing said bolt heads to their seats and holding them between the receiving and the discharge points, substantially as set forth.

18. An automatic bolt threading machine comprising a bed, a cutter-head, a work-carriage, means for operating said work-carriage, a rotary work-carrying turret journaled on said work-carriage, means for operating said turret step-by-step, means for securing said turret at each step in its movement, a magazine for feeding the work to said turret, a guide-chute for guiding said work to seats in the rim of said turret, said rim being formed with radial perforations and an internal recess adapted to receive and hold the bolt head, a shoe supported on an arm from a hub mounted around the axis of said turret, a spring guide mounted on the face of said shoe in position to force the work to its seat and hold the same between the receiving and the discharge point, and an adjusting screw for adjusting said spring guide, substantially as set forth.

In witness whereof, I have hereunto set my hand and seal at Washington, District of Columbia, this 22nd day of March, A. D. nineteen hundred and eleven.

ABRAHAM B. LANDIS. [L. s.]
